BENJAMIN FRANK THOMPSON, OF ARLINGTON, MARYLAND.

TELEGRAPH SYSTEM.

1,106,750

Specification of Letters Patent. Patented Aug. 11, 1914.

Application filed December 22, 1910. Serial No. 592,694.

To all whom it may concern:

Be it known that I, BENJAMIN FRANK THOMPSON, residing at Arlington, in the county of Baltimore and State of Maryland, have invented certain new and useful Improvements in Telegraph Systems, of which the following is a specification.

This invention relates broadly to an improved system for transmitting intelligence between distant points, and more particularly to an improved system whereby at least two messages may be sent simultaneously over a single line conductor.

One of the principal objects of the invention is to provide a system of the above character whereby balancing of the line may be eliminated.

Another object is to provide a system comprising terminal and a plurality of intermediate stations, whereby at least two messages may be transmitted between any two of said stations without interference.

Another object of my invention is to provide a system of the above indicated character such that a branch may be taken off at any point along the line.

A further object is to provide a system whereby any station along the line may transmit single, duplex, or diplex signals thereover.

The invention accordingly consists in the features of construction, combinations of elements and arrangements of parts which will be exemplified in the description hereinafter set forth, and the scope of the application of which will be indicated in the appended claims.

In the accompanying drawings which are to be taken as a part of this specification I have illustrated several of the preferred embodiments of my invention.

In these drawings, Figure 1 illustrates a system showing the same wire used both as a through or terminal station, and also as a 45 way-station wire; Fig. 2 illustrates a system, comprising a plurality of stations, whereby certain of the stations may be grouped to the exclusion of other stations; Fig. 3 is a view of the system, showing the 50 line as comprising a terminal and a divided or branch line station; Fig. 4 illustrates a different embodiment of the terminal apparatus from that disclosed in Fig. 3; Fig. 5 illustrates a modified form of the apparatus 55 illustrated in Fig. 4.

Before proceeding to describe with par-

ticularity the instrumentalities herein shown for carrying out my invention, it may here be noted that I combine means for impressing on the line an alternating current of the desired frequency, and means for separating the positive half waves of this current from the negative half waves with signaling apparatus, (herein shown as telegraph), such that certain of the apparatus is operated by 60 half waves of one polarity and the other apparatus by the half waves of opposite polarity.

Referring now to the drawings, and particularly to the embodiment of my invention shown in Fig. 1, A indicates one terminal station of a telegraphic circuit constructed in accordance with this embodiment of my invention. 1 indicates a source of alternating current, the same being indicated diagrammatically as an alternating current generator. This generator is interposed between ground 2 and the line 3. Leading from line 3 are wires 4 and 5 respectively, each of which is connected with terminals 6 and 7 of rectifying devices 8 and 9. Rectifier 8, in the present instance, is connected in such a way as to transmit the negative half of the alternating current wave, and rectifier 9 is connected to transmit the positive half of the alternating current wave. Leading from the terminal 10 of the rectifier 8 is a wire 11 which connects with the coil 12 of the telegraphic relay 13. Leading from coil 12 is the wire 14 connected with the ordinary telegraphic key 15, which operates with the contact 16 to close the circuit. The key 15 is provided with the side switch 17 as is usual in telegraphic practice. It will be understood, of course, 95 that the key 15 may be interposed at any point between the wire 3 and the line wire 18 which leads from the contact 16. 19 indicates a local circuit which includes the source of current or battery 20 and the telegraphic sounder 21, said circuit being adapted to be closed by the armature of the relay 13 in the usual manner of telegraphic apparatus. It will therefore be understood that the engagement of the key 15 with the 100 contact 16 will cause the negative half of the alternating current wave to pass through the rectifier 8, relay 13, and key 15 to the line wire 18; thence to ground in a manner hereinafter to be explained. Relay 13, in 105 the present instance, is the ordinary neutral relay, but it will be understood that a

polarized relay may be substituted therefor. The positive half of the alternating current wave passes through the wire 22 to the coil of the telegraphic relay 23, thence through 5 the wire 24, key 25, contact 26, line wire 18, as will be understood from the description hereinbefore given with regard to the positive half of the alternating current wave, and operates the telegraphic sounder 27 in 10 a manner which will be readily understood. Located in the other terminal B of this system is apparatus similar to that described in station A, the negative half of the alternating current wave passing from the wire 15 18 through the wire 28, rectifier 35, coil of the relay 32, wire 33, key 30, contact 29, wires 36 and 37 to ground. Rectifier 35 is so connected in the line as to transmit only the negative half of the wave received over 20 the line wire 18. Similarly, the rectifier 38 which is interposed between the line wire 18 and ground is connected in the line to transmit only the positive half of the alternating current wave, such wave operating the relay 39 to close the local circuit 40 in a manner which will be understood. The intermediate station C, which may be one of several interposed in the line wire 18 in this embodiment, is provided with telegraphic 25 apparatus operated by only one-half of the alternating current wave, the remaining half of said wave being shunted around the telegraphic apparatus by means of the wire 85, which wire includes the rectifier 86 so connected in said shunt as to permit passage 30 of the negative half of the alternating current wave. Any leakage through the rectifiers 51 or 86 is taken care of by the rectifier 52 in a bridge connected with the 35 wire between the rectifier 51 of the telegraphic apparatus and the rectifier 86 and the continuation of the line wire 18. One advantage of this arrangement of the system is that one-half of the alternating current wave is so utilized that it operates as a 40 way line, the other half being utilized as a direct line and connecting the terminal stations A and B.

By means of the construction and arrangement 45 of the various instrumentalities which comprise the system above described, it will be understood that two messages may be transmitted simultaneously from station A to station B or from station B to station A, or that single messages may be transmitted in opposite directions from either of said stations.

Considering, now, Fig. 2 of the drawings, A and B indicate the terminal stations. C 50 and D indicate two of various intermediate stations which may be interposed between the terminal stations in the line wire 18. The wire 18 is connected at either end with ground and provided with a source of alternating current supply herein indicated by

the generator 1. In this embodiment of the invention, the telegraphic relay 87 responds to the negative half of the alternating current wave, the positive half thereof being shunted around this relay as by means of 70 the wire 88, which includes the rectifier 89 so connected therein as to permit the passage of the positive half of the wave. The telegraphic relay 90 in station C is connected to respond to the positive half of the alternating current wave, the negative half being shunted around said relay as by means of the wire 91, and the rectifier 92 which is connected therein, to permit the passage of the negative half of the alternating current wave. Similarly, telegraph relay 93 in station D is connected in the line to respond to the negative half of the alternating current wave, the opposite half being taken care of by rectifier 94 included in the shunt 95. The apparatus in station B corresponds to that in station C, and is arranged to respond to the positive half of the alternating current wave. In the present embodiment it will be seen that stations A and D may communicate with each other simultaneously with a communication being carried on between the stations C and B. It will be obvious that a switch may be provided at any station by which the relay and key at that station may be cut in series with the rectifier of opposite sign. This will permit an operator along the line to communicate with any station irrespective of the connection of the apparatus to be called with the line.

Referring now to the embodiment of my invention illustrated in Fig. 3, the apparatus in the station A is similar in all respects to that shown in station A in Fig. 1 of the drawings, and therefore this apparatus will not be described herein, reference being made to the preceding part of the specification. Connected with the line wire 18 are branch wires 59 and 60 respectively. Although it will be obvious that either of these wires might be considered a main line, and the other a branch thereof, for the purpose of this description, both of these lines will be considered as branch. Branch 59 is connected through the rectifier 61, which separates out the negative half of the alternating current wave, with the coil of the telegraphic relay 62, which when operated closes the local circuit 63 through the sounder 64 in the usual manner. The wire 65 which leads from the coil of the telegraphic relay 62 is connected with the key 66 which co-operates with the contact, 67. Extending from contact 67 is a continuation of the branch line wire 59, said wire leading to a station herein designated at B'. The apparatus in this station is similar to the apparatus in the station designated C' except that no rectifier is required. Both stations work upon the negative half of the

130

alternating current wave which has been separated from the alternating current by means of the rectifier 61. The branch wire 59 extends from the telegraphic relay 69 of station B'' to ground or through other stations which may be interposed in this branch line circuit. The positive half of the alternating current wave passes through branch line wire 60, rectifier 70, the coil of the telegraphic relay 71, thence through wire 72 to the key 73, contact 74, thence through a continuation of the branch line wire 60 to the next station herein designated B', whence it passes through the wire 60 to ground. It will be understood of course that any desired number of stations may be interposed in this branch of the main line circuit. By means of the arrangement of the instrumentalities employed in this embodiment of my invention and their connection with the main line wire 18, a message may be sent from station A to all the stations along branch line 59 and simultaneously therewith a message may be sent from station A to any or all of the stations along the branch line 60. It will be understood that a message may be sent from any station in the branch line 59 to the station A and simultaneously with the sending of the message from any station in the branch line 60 to said station. Stations B' and C' or any similar stations which may be included in the branch line 60 may also communicate with each other simultaneously with the carrying on of communication between two or more stations in the branch line 59.

Referring to the embodiment of my invention shown in Fig. 4 of the drawings, the telegraphic apparatus in the station designated A is similar in all respects to that illustrated in the previously described Figs. 1 and 3. In this embodiment of the invention, however, means are employed to prevent leakage of the current of opposite sign through the rectifiers from interfering with the operation of the respective telegraphic apparatus in the station. This is accomplished by shunting the telegraphic relay 75 by wire 76 which includes a rectifier 77 so connected therein that any current of the opposite sign which leaks through the rectifier 8 will be carried around said relay 75. Similarly, rectifier 78 is included in a shunt 79 around the telegraphic relay 80, said rectifier being likewise so connected in said shunt as to carry the current of the opposite sign which may leak through the rectifier 9 and around said relay. It will be evident that by means of this construction and arrangement of parts that each of the telegraphic relays will receive the particular half of the alternating current by means of which it is to be operated. This same result may be accomplished by bridging the wires 11 and 22 by a bridge 81 and including in

said bridge a rectifier 82 as shown in the drawings. Rectifier 82 will be so connected as to conduct the leakages of opposite signs through the rectifiers 8 and 9 to their proper channels of flow. This last mentioned arrangement will result in the elimination of the shunting rectifiers 77 and 78. One advantage inherent in this last mentioned arrangement will be that all the current passing through either of the rectifiers 8 and 9 is delivered to the telegraphic apparatus through which it is intended to flow.

In Fig. 5 of the drawings, for the telegraphic apparatus in station A there has been substituted telephone receivers 83 and 84. The rectifier 8 delivers the negative half of the wave to the receiver 83 and the rectifier 9 similarly delivers the positive half of the wave to the receiver 84. Any leakage through the rectifiers is taken care of by rectifier 82 in the bridge 81 as has already been described in connection with the last described embodiment of my invention.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. It is also to be understood that the language used in the following claims is intended to cover all of the generic and specific features of the invention herein described and all statements of the scope of the invention, which as a matter of language, might be said to fall therebetween.

Having thus described my invention, what I claim as new and desire to secure by Letters Patent, is:

1. In a system of the class described, in combination, a line having divided portions throughout its length, a source of alternating current supply, signaling apparatus in the various divisions of said line, rectifying apparatus in the various divisions of said line, means associated with each signaling apparatus for opening and closing the circuit at will to impress signaling impulses upon the line, a bridge directly connecting the opposed members of each pair of divided portions, and rectifying means located in said bridge and so faced as to conduct to each side current pulsations of the wrong sign which have leaked through the rectifying means of each division.

2. In a system of the class described, the combination of a single line conductor provided throughout its length with a plurality of opposed divisions, a source of alternating current, signaling instruments in the various divisions of said line, rectifying means for permitting current pulsation of one sign only to be discharged through one

division and current pulsation of the opposite sign only to be discharged through the other division, a bridge directly connecting the opposed members of each pair of opposed divisions, and rectifying means located in said bridge and so faced as to conduct to each side current pulsations of the wrong sign which have leaked through the rectifying means of each division.

10 3. In a system of the class described, the combination with a line provided with a plurality of opposed divisions throughout its length, of a source of alternating current supply for said line, a plurality of signaling instruments located in each of said opposed divisions, rectifying means for supplying current pulsation of one sign through certain of said divisions and for supplying current pulsation of the opposed sign through the others of said divisions, the circuits through said divisions being normally closed, means associated with each instrument for impressing signaling impulses upon the line by opening and closing of the circuit at that point, a bridge directly connecting each pair of opposed divisions, and rectifying means located in said bridge and so faced as to conduct to each side current pulsations of the wrong sign, which have leaked through the rectifying means of each division.

4. In a system of the class described, the combination with a line, of a source of alternating current supply for said line, a plurality of signaling instruments in said line arranged to respond to current pulsations of different signs, rectifying means for allowing current pulsations of one sign to be

discharged through the instruments responsive to that sign, rectifying means for allowing current pulsations to be discharged through signaling instruments responsive to the opposite sign, and means for discharging current pulsations of a sign opposed to that for which each of said rectifying means is adapted to discharge through the signaling instruments associated therewith to their proper avenues of flow.

5. In a system of the class described, in combination with a line, a source of alternating current, a plurality of signaling instruments connected with said line, rectifying means for discharging current pulsations of one sign to certain of said instruments, rectifying means for diverting current pulsations of the opposite sign to the others of said instruments, and means for diverting through their proper avenue of flow, current pulsations of the opposite sign leaking through said rectifying means.

6. In a system of the class described the combination with a line, of a source of alternating current supply, a plurality of signaling instruments connected in said line, rectifying means for discharging through certain of said instruments current pulsations of one sign, and means for carrying current pulsations of the opposite sign around said instruments.

In witness whereof I affix my signature 70 in the presence of two witnesses.

BENJAMIN FRANK THOMPSON.
